UNITED STATES PATENT OFFICE

92,834

DESIGN FOR AN ELECTRIC FLAT IRON

Alexander Bertea, Winsted, Mass., assignor to
The Fitzgerald Manufacturing Company, Tor-
ington, Conn., a corporation of Connecticut

Application March 26, 1934, Serial No. 51,196

Term of patent 7 years

To all whom it may concern:

Be it known that I, ALEXANDER BERTEA, a citizen of the United States, residing at Winsted, county of Litchfield, and State of Connecticut, have invented a new, original, and ornamental Design for an Electric Flat Iron, of which the following is the specification, reference being had to the accompanying drawing forming part thereof.

In the drawing:—

Fig. 1 is a top plan view of an electric flat iron showing my new design;

Fig. 2 is a side elevation of the same; and

Fig. 3 is a front view thereof.

I claim:

The ornamental design for an electric flat iron, as shown.

In testimony whereof, I affix my signature.

ALEXANDER BERTEA.
